UNITED STATES PATENT OFFICE.

SAMUEL H. LEWIS, OF RICHMOND, VIRGINIA.

POWER REVERSE-GEAR.

1,252,458.

Specification of Letters Patent.

Patented Jan. 8, 1918.

Application filed October 18, 1915. Serial No. 56,487.

To all whom it may concern:

Be it known that I, SAMUEL H. LEWIS, a citizen of the United States, residing at Richmond, in the county of Henrico and State of Virginia, have invented certain new and useful Improvements in Power Reverse-Gears, of which the following is a specification.

My invention relates to improvements in fluid pressure operated apparatus for operating or shifting the valve gear of steam engines, particularly railway locomotives, while not necessarily restricted to this use.

An important object of this invention is to simplify apparatus of the above mentioned character, and particularly to obviate the necessity of providing positive locking means to prevent undesired movement of the piston in the power cylinder.

Another object of this invention is to provide means to prevent waste of fluid pressure at the exhaust port of the operating valve.

A further object of the invention is to provide means for resisting undesired movement of the piston in the power cylinder by opposing such undesired movement with an increase of pressure on the side of the piston in the direction in which it starts to move and a decrease of pressure on the opposite side of the piston.

Other objects and advantages of the invention will be apparent during the course of the following description.

In the accompanying drawings forming a part of this specification and in which like numerals are employed to designate like parts throughout the same,

Figure 1 is a side elevation of apparatus embodying my invention, showing the same applied to a railway locomotive,

Fig. 2 is a detail side elevation of a pivot joint,

Fig. 3 is a detail sectional view taken on line 3—3 of Fig. 2,

Fig. 4 is an end elevation of the apparatus.

Fig. 5 is a central vertical longitudinal sectional view through the power cylinder, embodied in the apparatus,

Fig. 6 is a transverse sectional view taken on line 6—6 of Fig. 5,

Fig. 7 is an elevation of the inner side of the apparatus,

Fig. 8 is a side elevation of the valve casing,

55

Fig. 9 is a sectional view taken on line 9—9 of Fig. 8,

Fig. 10 is a horizontal sectional view taken on line 10—10 of Fig. 9,

Fig. 11 is an elevation of a rotatable valve, 60 and,

Fig. 12 is a diagrammatic view of ports formed in the valve casing.

In the drawings, wherein for the purpose of illustration is shown a preferred embodiment of my invention the numeral 10 designates the boiler of a railway locomotive, equipped with the cab 11, as is customary. The numeral 12 designates a preferably horizontally arranged power cylinder, preferably disposed beneath the boiler 10 forwardly of and near the cab 11, while the cylinder may be attached to any other suitable part of the locomotive. This cylinder is rigidly secured to the boiler 10 by any suitable means.

As more clearly shown in Fig. 5, a piston 13 is disposed to reciprocate within the cylinder 12, and is rigidly connected with a preferably tubular piston rod 14, the rear 80 end of which has screw-threaded engagement with a plug 14', as shown.

As clearly shown, in Fig. 5, this piston rod preferably but not necessarily has portions 15 and 16, of different diameters, the portion 15 having the smaller diameter. The forward reduced portion 15 of this piston rod operates through a forward stuffing box 17, carried by a head 18, while the rear large portion 16 of the piston rod operates through a rear stuffing box 19, carried by a head 20. The function of having the portions 15 and 16 of the piston rod of different diameters will be apparent hereinafter. The piston 13 is provided with a 95 tapered opening 25, receiving a corresponding tapered portion 21' of the rod 14, and a clamping nut 22' locks the piston to this rod, as shown.

The piston 13 is provided upon its periphery and at a point equidistantly spaced from its ends with an annular groove 21, receiving an inner metallic packing ring 22 and outer packing rings 23, preferably formed of rubber or the like. Upon its 105 periphery and at its ends, the piston 13 is

provided with annular grooves 24, receiving interfitting metallic rings 25, L-shaped in cross-section, as shown. I have found that this combination of packing rings prevents the leakage of pressure between the piston and the cylinder 12, in a highly satisfactory manner.

The forward end of the rod 14, is pivotally connected, as shown at 26, with a piton or link 27, pivotally connected, as shown at 28, with a vertical crank or arm 29, rigidly mounted upon a transverse lift or rock shaft 30. Each end of the lift or rock shaft 30 has a horizontal arm 31, rigidly connected therewith, which is connected with the vertically movable link (not shown) of the valve gear. It is to be understood that the invention is in no sense restricted to operating any particular type 20 of valve gear as it is adapted for use in connection with various types.

Rigidly connected with the forward end of the piston rod 14 is a depending arm or crank 32, having its lower end pivotally connected with a link 33, pivotally connected with the lower end of a preferably vertically swinging lever 34. The vertically swinging lever 34 (see Figs. 2 and 3), is provided between its ends with a longitudinal opening 35, receiving a flat lug or extension 36, formed integral with a pivot element or bolt 37. This pivot element or bolt is rotatably mounted in an opening 38 extending transversely through the end of a bracket 39. The flat lug or extension is provided with a screw-threaded longitudinal opening 40, receiving an adjusting screw 41. The opening 35 is longer than the lug 36, and the adjusting screw 41 engages the end walls of this opening. It is obvious that by turning the adjusting screw 41 it will be shifted longitudinally with respect to the lug 36 and will hold the lever 34 at a different position with respect thereto, whereby the pivot point of this lever may be adjusted up and down. Formed upon the lug 36 is a screw-threaded extension 42, receiving a nut 43, having a washer 44, preferably interposed between the nut and the lever 34. The function of adjusting the pivot of the lever 34 is to regulate the operation of the piston with respect to returning the controlling valve to the neutral position.

Pivotally connected with the upper end 55 of the lever 34, as shown at 45, is a preferably longitudinally adjustable or extensible reach rod 46, as shown.

The numeral 47 designates a valve structure as a whole, comprising a casing or casting 48, having a flat face 49 and provided with an inlet port 50, communicating with a pipe 51, which leads to a source of pressure, such as a compressed air storage tank (not shown). This inlet port communicates 65 with an inlet port 52, passing through an

annular flange 53, formed upon the casing 51, as shown. Arranged upon opposite sides of the inlet port are pairs of ports 54, 55; 56, 57, which lead into pipes 58 and 59, discharging into the opposite ends of the cylinder 12. The pairs of ports 54 and 55 have their upper ends discharging into a pair of non-communicating spaced segmental surface ports 60 and 61 respectively; while the pairs of ports 56 and 57 have their upper ends leading into non-communicating segmental surface ports 62 and 63 respectively. Each pair of ports 54, 55 or 56, 57 lead into a chamber 53', as shown. At its lower end, the chamber 53' has screw-threaded engagement with a tube 54', extending upwardly therein, as shown. The upper end of this tube serves as a guide for a check ball valve, normally closing the end of the port 55 or 57, and this ball valve is normally held seated by a spring 56' as shown. The tube 54' has apertures 58', arranged beneath the ball valve. The tube 54' is internally screw-threaded to receive one of the pipes, leading to the power cylinder. The numeral 64 designates an exhaust port, arranged centrally with respect to the segmental surface ports, as shown.

Mounted to rotate within the flange 53 in slidable contact with the face 49 is a valve 65, having its inner side provided with a surface groove or port 66, the inner end of which is in permanent registration with the exhaust port 64, while its outer end is adapted to be alternately moved into registration with the segmental ports 60 and 62. The valve 65 is provided in its lower portion with a transverse port or opening 67, arranged between the segmental grooves 61 and 63, and when the valve 65 is in the normal position the opening 67 preferably has its ends arranged in line to line relation with the grooves 61 and 63, whereby a leakage of pressure is permitted into the ports 61 and 63, such pressure passing to the opposite ends of the cylinder 12, to normally retain the pressure equal upon opposite sides of the piston 13. The inlet port 52 discharges into a chamber 68, disposed between the valve 65 and a head 69, which closes this chamber. The pressure from the port 50 is thus circulated upon the top of the valve 65, and serves to retain it securely seated.

The valve 65 is provided with a post 69', for turning it, which post is rectangular in cross-section and adapted to fit within an opening 70, formed in a head 71 of a stud 72, rigidly connected with a pinion 73. The head 71 is adapted to contact with a washer 74, and a compressible coil spring 75 is arranged between the post 69' and the end wall of the opening 70, thus serving to hold the valve upon its seat and the head 71 in contact with the ring or washer 74 for preventing leakage.

The head 69 is provided with a flange 76, forming with a ring or collar 77, an annular groove 78, for receiving a suspension collar or strap 79. This suspension collar or strap is provided at its lower end with a depending apertured knuckle 80 carrying a pivot element 81. The reach rod 46 has its rear end apertured for receiving the pin 81, whereby it is pivotally connected with the 10 knuckle 80. The pin 81 extends outwardly into a longitudinal opening or slot 82, formed in the lower end of a vertically swinging combination lever 83. This combination lever extends upwardly for pivotal connection with a controlling lever 84, by means of a pin 85 or the like. This controlling lever carries the ring 77, which is preferably formed integral therewith and pivotally mounted upon the flange 53. Rigidly 15 connected with the upper portion of the combination lever 83, by means of bolts 86 or the like, is a toothed segment or gear 87, engaging the pinion 73, for turning it.

The control lever 84 operates in proximity 20 to a stationary toothed quadrant 88, rigidly secured to the upper ends of stationary arms 89 formed integral with the casing 48. The lever 84 is provided with latch means 90, to coöperate with the toothed quadrant to lock 25 the lever in adjustment at the desired position.

The operation of the apparatus is as follows:

When the control lever 84 is in the normal 30 or neutral position, the rotary valve 65 is in the normal or neutral position, whereby the ends of the admission port 67 are arranged substantially in line to line relation with the inner or lower ends of the surface ports 61 and 63. There is then a passage of fluid 35 pressure from the port 67 into the lower segmental ports 61 and 63, which pressure is conducted through the pipes 58 and 59 to the opposite ends of the outer cylinder 12, upon opposite sides of the piston 13, thus 40 equalizing the pressure upon such opposite sides and tending to hold the piston against movement. By having the portion 15 of the rod 14 of smaller diameter than the portion 45 16, this equal pressure will operate upon a slightly larger surface, upon the side of the piston 13, adjacent the reduced portion 15 of the rod 14, and this increased surface is sufficient to overcome the tendency that the elements of the valve gear have to move downwardly by gravity. While the pressure is 50 thus capable of being constantly supplied into the opposite ends of the cylinder 12, by virtue of the line to line position of the ends 55 of the port 67 with the ends of the port 63, the pressure within the opposite ends of the cylinder 12 cannot circulate in a reverse direction, through the pipes 58 and 59, to the source of pressure, as the upwardly seating 60 valves 55 close the ends of the ports 55,

while the ports 60 and 62 which are exhaust ports, are closed, when the valve 65 is in the neutral position. It is thus apparent that pressure, which passes into the opposite ends of the cylinder 12, is entrapped therein and 70 any perceptible improper movement of the piston, will rapidly increase pressure, thus serving to positively hold the piston 13 against any extensive improper movement. For illustration, if the piston 13 should 75 move from its adjusted position, with a pressure of one hundred pounds per square inch on its opposite sides, for the distance of three-sixteenth of an inch, there will be developed a resistance of approximately one 80 hundred and fifty pounds to further undesired travel of the piston, due to the compression and expansion of the fluid pressure on its opposite sides, thus rendering it impossible for the piston to move to any considerable extent or sufficiently to cause perceptible operation of the parts of the apparatus.

When it is desired to shift the valve gear 90 to drive the locomotive forwardly the control lever 80 is swung forwardly. When this is done, the upper end of the combination lever 83 is swung forwardly, carrying with it the segmental gear 87, whereby the pinion 73 is carried clockwise. This clockwise movement of the pinion 73 turns the valve 65 clockwise, whereby the upper end of the port 66 is moved into registration with the segmental groove 62 and the port 67 is moved into registration with the port 61. It is thus apparent that pressure will 100 pass through pipe 51, port 52, chamber 68, port 67, port 61, port 55, pipe 58, into the left end of the cylinder 12, while pressure will exhaust from the opposite end of the 105 cylinder through pipe 59, port 54, port 62, port 66, and port 64, to the atmosphere. The piston 13 is then moved forwardly whereby the rod 14 and associated elements operate the valve gear to drive the locomotive forwardly. Upon this forward movement of the rod 14, the depending arm 32 is moved forwardly swinging the lower end of the lever 84 forwardly and its upper end rearwardly. The rearward movement of 110 the upper end of the lever 84 is transmitted to the reach rod 46, and by it to the combination lever 83. The lever 84 being locked in the new position by the latch means 90, the combination lever 83 will turn upon the pin 125 85 as a pivot and when its lower end is swung rearwardly the segmental gear 87 is swung rearwardly, whereby it turns the pinion 72 counter-clockwise, returning the valve 65 to the neutral position. When the valve 120 65 is returned to its neutral position, the pressure equalizes upon opposite sides of the piston 13. By this means the extent of movement of the piston in either direction is always proportional to the movement of 130

the control lever in the same direction. When the control lever 84 is swung rearwardly the reverse of this operation takes place as is thought to be obvious from the foregoing description.

It is to be understood that the form of my invention herewith shown and described is to be taken as a preferred example of the same, and that various changes in the 10 shape, size, and arrangement of parts may be resorted to without departing from the spirit of the invention or the scope of the subjoined claims.

Having thus described the invention, what 15 I claim is:—

1. In apparatus of the character described; a cylinder; a piston mounted to move within the cylinder; a valve gear operated by the movement of the piston; a 20 valve seat having two separate surface supply ports and two separate surface exhaust ports arranged about an exhaust opening which communicates with the atmosphere; chambers having ports leading to the surface supply ports and ports leading to the surface exhaust ports; a movable valve having 25 a surface port in permanent communication with the exhaust opening of the valve seat and adapted to be alternately moved into communication with the exhaust surface ports and a pressure supply port normally in line to line relation with the surface supply ports to permit of the simultaneous supply of pressure through both 30 surface supply ports and to be moved in one direction for covering one surface supply port and opening the other surface supply port; pipes having communication with the chambers and with the opposite ends of the cylinder; check valves arranged within the chambers and adapted to close the ports which lead to the surface supply ports; and means to supply pressure to the pressure supply port 35 of the movable valve.

cylinder; and means to supply pressure to 40 the pressure supply port of the movable valve.

2. In apparatus of the character described; a cylinder; a piston mounted to move within the cylinder; a valve gear operated by the movement of the piston; a valve seat having two separate surface supply ports and two separate surface exhaust ports arranged about an exhaust opening which communicates with the atmosphere; 50 chambers having ports leading to the surface supply ports and ports leading to the surface exhaust ports; a movable valve having a surface port in permanent communication with the exhaust opening of the valve seat and adapted to be alternately moved into communication with the exhaust surface ports and a pressure supply port normally 55 in line to line relation with the surface supply ports to permit of the simultaneous supply of pressure through both surface supply ports and to be moved in one direction for covering one surface supply port and opening the other surface supply port; pipes having communication with the chambers and with the opposite ends of the cylinder; check valves arranged within the chambers and adapted to close the ports which lead to the surface supply ports; and means to supply pressure to the pressure supply port 60 of the movable valve.

In testimony whereof I affix my signature in presence of two witnesses.

SAMUEL H. LEWIS.
